UNITED STATES PATENT OFFICE.

JOSEPH WAHL, OF NEW YORK, N. Y.

CRATE.

1,027,631.

Specification of Letters Patent. Patented May 28, 1912.

Application filed February 1, 1912. Serial No. 674,795.

To all whom it may concern:

Be it known that I, JOSEPH WAHL, a citizen of the United States of America, residing in New York, in the borough of Manhattan, in the county and State of New York, have invented certain new and useful Improvements in Crates, of which the following is a specification.

This invention relates to an improved foldable or collapsible crate which is intended for the purpose of shipping ladies' hats, artificial feathers, trimmings and similar light articles on the one hand, and hardware, flowers, fruits, confectionery, and other heavier articles on the other hand, in a perfectly secure and protected manner, the crate being folded up after use so as to take up less room in storage and being readily made up in crate-form again when it is desired to use the same for delivering articles to customers.

Heretofore hats and other articles for ladies' use were shipped in collapsible cardboard boxes which were strengthened by means of wooden frames on the bottom-side and end-walls of the box. These boxes were found unsuitable for many purposes, especially when heavier and bulkier articles of merchandise are to be shipped.

The object of this invention is to furnish an improved collapsible shipping crate which is made mainly of wood and partly of card-board and strengthened in such a manner that any article from a light and flimsy article of fashion for ladies' use up to a heavier article can be safely shipped so that the range of application of such crates may be largely extended for use in the various trades without being confined to the special uses of the millinery, feather and artificial flower trades; and for this purpose the invention consists of a collapsible or foldable crate, which comprises a bottom made of longitudinal and transverse wooden slats, side-walls hinged to the sides of the bottom and also made of longitudinal and transverse strips of wood, and front and rear-walls pivoted to front and rear-slips of the bottom and made of wooden slats like the side-walls, and a cover constructed and made of slats in the same manner as the bottom and provided with corner-slots which are used in connection with double sheet metal double fasteners of rectangular shape that are fulcrumed to the upper corners of the side-walls, one section of each fastener be-

ing adapted to be passed through the slots in the cover and the other section through slots in the corners of the front and rear-walls for firmly holding the side and front and rear walls together and the cover in locked position thereon while permitting the convenient detaching of the fasteners and from said slots the inward folding of the side-walls and the front and rear-walls over the bottom and storing them with the cover in collapsed position ready for another use.

In the accompanying drawings, Figure 1 represents a perspective view of my improved shipping crate, Figs. 2 and 3 are respectively a vertical longitudinal and a vertical transverse section on lines 2-2 and 3-3, Fig. 1, Fig. 4 is a plan-view of the body-portion of the crate, shown in folded condition and with the top or cover removed, Fig. 5 is a top-view of the cover, Figs. 6 and 7 are respectively vertical transverse sections on lines 6-6, Fig. 4, and 7-7, Fig. 5, Fig. 8 is a perspective view of one of the double fasteners by which the walls and cover of the crate are connected with each other, and Figs. 9 and 10 are detail sections of the upper corners of the crate taken respectively at right angles to each other and showing the double fasteners in locked position.

Similar letters of reference indicate corresponding parts throughout the several figures of the drawings.

My improved crate is constructed of six main-parts: a bottom *a*, a front-wall *b*, a rear-wall *d*, two side-walls *c*, *c'*, and a top or cover *e*. The bottom *a* is made of transverse slats *a'*, side-strips *a²* and an interior lining of card-board *a³*. The cover *e* is made detachable from the body-portion and constructed in the same manner as the bottom *a* of transverse slats *e'* and longitudinal front and rear end-strips *e²*, which are connected by means of suitable brads at the ends and covered by an interior lining of card-board *e³* which are likewise attached to the slats by means of brads. The cover is furthermore provided with narrow interior cleats *e⁴* which correspond with the shape of the body-portion of the crate so as to fit accurately into the walls of the same when they are connected for use.

The side-walls *c*, *c'* are made of thin upright slats *c²* which are arranged at suitable distances from each other and connected by longitudinal holding strips *c³* at their upper and lower ends, while the front and rear-

walls are made in the same manner of upright slats and narrow connecting strips, which like the longitudinal strips of the side-walls are mortised for receiving the upright slats and connected together by means of brads in the same manner as the slats and edge-strips of the bottom and cover. The inner sides of the side-walls as well as the inside of the front and rear-walls are covered with cardboard that is attached by means of brads in the same manner as in the bottom and cover.

To the front and rear-edges of the bottom *a* are attached raised strips *f* which are equal in thickness with the longitudinal strips of the front and rear-walls and to the faces of the ends of these raised strips *f* are applied vertical sheet-metal plates *f*¹ which are extended beyond the ends of the strips *f* and to which the lower longitudinal strips *c*³ of the side-walls *c*, *c'* are connected by pivots *f*². The lower longitudinal strips of the side-walls *c*, *c'* are rounded off at their inner lower corners, also the lower ends of the upright slats so as to permit the free inward folding of the side-walls *c*, *c'* on their pivots onto the bottom *a*.

To the transverse ends of the front and rear-strips *f* are further applied upright sheet metal plates *f*³ which extend in vertical direction above the front and rear-strips *f* and which serve for pivoting thereto at *f*⁴ the front and rear-walls *b* and *d* so as to permit of their being folded over the folded-down side-walls, as shown in Figs. 4 and 6.

The upper longitudinal strips of the front and rear-walls *b* and *d* are provided near their ends and in line with the inner edges of the side-walls with transverse slots *o* for the purpose of permitting the convenient introduction of the lower arms of double fasteners *g* of angular shape which are fulcrumed at their apices to the inside of the upper corners of the side-walls *c*, *c'* the arms of the double angular fasteners being long enough to extend through an upper portion of the longitudinal strips of the front and rear-walls and then to be bent over the same so as to hold the side and the front and rear-walls firmly together in upright position, as shown in Fig. 1.

The upper arms of the double-fastener *g* extend at right angles to the lower arms and serve for the purpose of being passed through slots *o'* in the corners of the cover *e*, after which the ends of the upper arms of the fasteners are bent over the cover, as shown in Fig. 1, completing thereby the crate. When the side, front and rear-walls are thus connected by the lower arms of the double fasteners and the cover held in position on the walls by the upper arms of the double fasteners as described, a strong and efficient shipping crate is obtained which

is strong enough to resist even comparatively rough handling and which fully protects the articles placed therein, whether they are light articles of fashion, but also heavier articles of merchandise up to from 100 to 150 lbs. in weight.

In addition to the holding together of the body and cover by the double fasteners described, there may be applied suitably-sealed locking wires for preventing the removal of the cover while the goods are in transit.

When the goods arrive at their destination they are removed from the crates and the latter are then folded up into collapsed state by disengaging first the cover from the body, which is done by bending up the upper arms of the fasteners so as to slip them through the slots in the cover, then straightening up the lower arms of the fasteners and removing the front and rear-walls by swinging them in outward direction, then swinging the double fasteners on their fulcrum toward the inside of the side-walls as shown in dotted lines in Fig. 4, folding the side-walls downwardly over the bottom, and then folding the front and rear-walls over the side-walls, as shown in Fig. 4.

When it is desired to ship articles requiring ventilation, the interior linings of card-board can be omitted from the side and rear-walls in which case the crate can be used as a collapsible return-crate for the shipment of fruits, eggs and other perishable articles of food.

The improved shipping crate can be manufactured at a comparatively small cost, as all the wooden parts can be cut to the proper size, the pivot-plates and the angular fasteners stamped out by means of dies, and the crate then assembled as required, either with or without the interior linings of cardboard, forming thereby a collapsible shipping crate which can be used advantageously for the shipment of articles in many different trades.

I claim:

1. A shipping crate comprising a bottom, a side wall having a hinge connection with said bottom, an adjacent side wall having a hinge connection with said bottom, a cover, and an angular fastener pivoted at its angle to one of said walls at one corner thereof and having a horizontal arm adapted to engage and lock the other wall and a vertical arm engaging the cover and adapted to lock thereover.

2. A shipping crate comprising a bottom, a side wall having a hinge connection with said bottom, an adjacent side wall having a hinge connection with said bottom, one of said side walls being provided with a slot, a cover provided with a slot, an angular fastener pivoted to one of said walls at one corner thereof and having an arm composed of flexible sheet metal adapted to engage said slotted side wall and being bendable over

against the outer face thereof for locking said side wall in upright position, and a vertical arm adapted to engage the slot of said cover and composed of sheet metal bendable into contact with the outer face of said cover for locking the same.

3. A shipping crate comprising a bottom, a side wall having a hinge connection with said bottom, an adjacent side wall having a hinge connection with said bottom, one of said side walls being provided with a slot, a cover provided with a slot, an angular fastener pivoted to one of said side walls at one corner thereof and having a horizontal arm engaging the slotted side wall and composed of two layers of sheet metal bendable in opposite directions into contact with the outer face of said side wall for locking the same in vertical position and a vertical arm 20 engaging said slotted cover and composed of two layers of sheet metal bendable in opposite directions into contact with the outer face of said cover for locking it in closed position.

25 4. A shipping crate, comprising a bottom, raised strips applied to the front and rear-edges of said bottom, side-walls hinged to opposite ends of said strips, and provided with slots in its upper corners, front 30 and rear-walls also hinged to the front and rear strips of the bottom, a cover having slots in its corners, angular double fasteners

fulcrumed to the upper corners of the side-walls and adapted to be passed through the slots in the upper corners of the front and rear-walls, and the slots in the corners of the cover, and folded over the same.

5. A shipping crate comprising a bottom, raised strips attached to the front and rear-edges of said bottom, extension-plates attached to the ends of the front-and rear-strips, side-walls pivoted to said extension-plates, extension-plates attached to the ends of the strips at right angles to the first set of extension-plates, front and rear-walls 45 pivoted to said second set of extension-plates, said front and rear-walls being provided with transverse slots in their upper corners, a cover provided with slots in its corners, and angular double fasteners fulcrumed at 50 their apices to the upper corners and inside of the side-walls, the arms of said fasteners being adapted to be passed through the slots of the front and rear-walls, and of the cover for locking the side, front and rear-walls 55 and the cover together.

In testimony, that I claim the foregoing as my invention, I have signed my name in presence of two subscribing witnesses.

JOSEPH WAHL.
